Des. 223,669
Patented May 23, 1972

223,669

ELECTRON MICROSCOPE

Seiichi Nishino, Kazuyoshi Kato, and Hiroshi Akahori,
Katsuta-shi, Japan, assignors to Hitachi, Ltd., Tokyo,
Japan

Filed Feb. 13, 1970, Ser. No. 21,427

Term of patent 14 years

Int. Cl. D16—08

U.S. Cl. D26—5

FIG. 1

FIG. 3

FIG. 5

FIG. 1 is a right side, top and front perspective view of an electron microscope showing our new design,
FIG. 2 is a front elevational view thereof,
FIG. 3 is a top plan view thereof,
FIG. 4 is a left side view thereof,
FIG. 5 is a rear elevational view thereof.

We claim:

The ornamental design for an electron microscope, as shown.
